VENDING MACHINE

John Fritsche, Merion, and Joseph C. Hadik,
Philadelphia, Pa.; said Hadik assignor to said
Fritsche

Application February 20, 1929. Serial No. 341,322

2 Claims. (Cl. 312—37)

The object of this invention is to devise a novel construction of a vending machine adapted for vending articles in package form or articles which can be strung upon a supporting element.

5 This type of vending machine is especially adapted to vend articles by discharging them into a position accessible to the intending user for only temporary use, or they may be discharged in such a manner that the purchaser can take them 10 away.

In our prior Patent No. 1,437,970 patented December 5, 1922, we have described and broadly claimed a vending machine which embodies the foregoing features, but it was necessary for 15 the intending purchaser, after the insertion of a coin of the proper denomination, to rotate a handle to release the article removing mechanism. In this invention the coin releases the stop which permits the operative stroke of the 20 article removing mechanism.

With the above in view, our invention comprehends a novel vending machine.

It further comprehends novel means for supporting the articles, novel means for removing 25 an article and discharging it into a position accessible to the user, and novel means for ensuring a full stroke of the article removing member.

Other novel features of construction and ad- 30 vantage will hereinafter appear in the detailed description and the appended claims.

For the purpose of illustrating the invention, we have shown in the accompanying drawings a preferred embodiment of it, which, in practice, 35 will give satisfactory and reliable results. It is, however, to be understood that this embodiment is typical only and the various instrumentalities of which our invention consists can be variously arranged and organized, and the invention is not 40 limited to the exact arrangement and organization of these instrumentalities as herein set forth.

Figure 1 is a perspective view of a vending machine embodying our invention.

45 Figure 2 is a front elevation of the article containing cabinet with its door in its open position.

Figure 3 is a sectional view on line 3—3 of 50 Figure 1 showing more clearly certain features of the article removing mechanism.

Figure 4 is a sectional view showing certain of the parts seen in Figure 3 in a different relation from that seen in said Figure 3.

55 Figure 5 is a front elevation of a portion of the article removing member.

Similar numerals of reference indicate corresponding parts.

Referring to the drawings:

1 designates a vending machine embodying our invention. The vending machine is provided 60 with a lower cabinet 2 having an open top 3, thereby forming a chamber to receive articles which have been temporarily used.

The lower cabinet is provided with front angles 4 and rear angles 5 which latter carry at their upper ends the article receiving cabinet or casting 6 containing the articles to be vended. The cabinet 6 is provided with a single door 7 secured thereto by hinges 8 and provided with a key controlled lock 9. The door 7 is provided with a coin slot 10 and an opening 11 through which a coin is returned which did not operate the machine. The door is cut away to form an article delivery opening 12 through which an article can be removed.

75 The article receiving cabinet 6 is provided with an article receiving chamber 13, which at its lower end is provided with an upwardly extending guard 14 in the form of a plate carried by the bottom and the rear wall of the cabinet 6. Above 80 the door 7 is a slot 15.

The article retainer

The article retainer consists of a longitudinally extending bar 15 having a slot 16 extending longitudinally through it and opening through its top. The top edges are smooth instead of notched as in our prior Patent No. 1,437,970. The forward end of the article retainer is provided with a downwardly and forwardly extending terminal 16' which is apertured to receive one end of a cable 17 detachably secured thereto by means of a pin 18.

85 If a permanent sale is to be made of the article to be vended the cable 17 may be omitted. The bar 15 is secured in position by means of a screw 19 in the same manner as in our prior patent, and is also supported by a spring pressed bracket 20 pivotally supported by the rear wall of the article receiving cabinet and retained by its 90 spring against the angle 21, so that it will open in the direction in which an article is to be moved when removing it from the article retainer.

95 The bar 15 has fixed to it one end of a flat spring 22, the forward end of which terminates in proximity to the terminal, beneath an aperture 23. The cable 17 is looped into the chamber 3 and has one end secured within the cabinet 6 in any desired manner. The articles 24 to be vended are strung upon the article retainer in any 105 110

desired manner and if the articles are towels as illustrated, they may be provided with grommets 25.

The article removing mechanism

The article removing member 26 is in the form of a plate slidable on a bar 27 and provided with a grasping handle 28 which extends through the slot 15' in the front of the cabinet 6. The article removing member 26 has pivoted to it at 29 a lever 30 having its bottom curved and provided at one end with a hook 31 and at its opposite end is pointed as at 32.

15 A spring 33 tends to move the pointed end 32 downwardly. A cam 34 carried by a bracket 35 is in the path of the lever 30 when the latter approaches the end of its rearward stroke. The article removing member 26 has a hook 36 pivoted to depending arms 37 and has a lug 38 normally 20 contacting with one of said arms due to the action of a spring 39. The hook 36 has a plurality of shoulders 40. The article removing member 26 is also provided with a depending plate 41 from which projects laterally a cam 42 having 25 the upper cam face 43 and the lower cam face 44. This cam controls the coin mechanism which will now be described.

The coin mechanism

30 Our present invention is preferably coin controlled in order that the purchaser at the time of purchase will deposit the proper amount in the machine. The coin or check of the proper denomination is inserted in the coin slot 10 and passes
35 through the coin chute 45 and into a coin retainer 46. One side of the coin chute is pivoted and acted upon by a spring 47 which tends to retain the pivoted side in closed position. The bottom of the coin retainer is normally closed
40 by a coin stop 48 in the form of an angle guided in a bracket 49 and having a shoulder forming recess, a wall of which interlocks with the bracket 49 as clearly set forth in our prior Patent No. 1,437,970.

45 The coin stop 48 has one end pivoted to a lever
50 which in turn is pivoted to a vertically mov-
able arm 51 suitably guided and cut away at its
upper end to form a shoulder 52. The member
51 carries an anti-friction roller 53. A second
55 member 54 is guided for vertical movement on
the door and is provided with a roller 55. The
lower end of this member 54 is pivotally connected
at 57 to a cam plate 56, the lower end of which
55 has a bottom cam face 58 riding on a coin retained
in the coin retainer 46.

59 is a return chute leading to the coin return opening 11 and 60 is a coin box which received the coins discharged from the coin retainer 46. The coin slot 10 when the machine is not in operating condition is closed by means of a plate 61 constructed and operated similar to that shown in our prior Patent No. 1,437,970.

The pivoted cam plate 56 has one end of a spring 62 connected to it, the other end of such spring being connected to a fixed point, and a spring 63 has one end secured to a fixed point and the other to a coin stop 48 so that when the latter is released it will become disengaged from the bracket 49 and will move to the left of the position seen in Figure 2.

The operation of our novel vending machine will now be apparent to those skilled in this art and is as follows:—

By releasing the screw 19 the article support 15 can be removed and the articles, such as for example

ample, the towels 24, are strung on the article support 15 which is then reinserted in place and locked in position by the screw 19. The door 7 is closed and locked and the machine is now ready for operation.

It will be understood that in accordance with this invention the articles can be vended for temporary use only or can be vended in such a manner that they can be taken away by the purchaser.

Assuming now that an intending purchaser inserts a coin or check of the proper denomination in the coin slot 10, such coin will pass through such coin slot and the coin chute 45 and is received in the coin retainer 46 and comes to rest against the coin stop 48 which at this time closes the bottom of the coin retainer 46. The intending purchaser now takes hold of the grasping portion 28 of the article removing member 26 and moves it towards the left of the position seen in Figure 1.

The cam face 44 riding up on the roller 55 will cause the member 54 to move downwardly thereby rocking the cam member 56 on its pivot and the cam face 58 engaging the periphery of the coin will press the latter downwardly against the coin stop member 48 thereby causing the latter to move downwardly and be released from the bracket 49 and the spring 63 will move the coin stop 48 to the left of the position seen in Figure 2 so that the coin which has operated the main chime will drop into the coin box 60. 105

As the coin stop 48 moves to the left it rocks the lever 50 on its pivot thereby causing a downward movement of the member 51 so that the shoulder 52 is moved out of engagement with a shoulder 40 of the stop 36, see Figures 2 and 5, so that the article removing member 26 is now free to continue in its movement towards the left. As the article removing member moves towards the left the article receiving lever 30 passes into the slot 16 in the article support 15 and the hook 31 passing beneath a grommet 25 will take hold of the nearest article 24 so that when the operator moves the article removing member 26 towards the right the article will be carried with it. The grommet 25 passing over the hook 31 rocks the lever 30 and will cause the hook 31 to be drawn downwardly so that the pointed end 32 will be held in such position that it cannot drop into the aperture 23 in the article support and also raise it sufficiently so that the pointed end 32 will be in the path of the cam face of the cam 34. 110 115 120 125

The continued movement toward the right of the article removing member causes the rocking 130 of the article carrier 30 so that the grommet of the article slides over the delivery end of the article support and over the terminal 16'. It will be apparent that as the grommet of the article which is being removed passes along the retainer 135 15, it will come into engagement with the spring 22 so that as the article carrier is rocked upwardly by the cam 34 the spring will facilitate the removal of the grommet from the hook 31. If the cable 17 is employed the article drops down on 140 such cable and into a position accessible to the purchaser and can be removed through the delivery opening 12 for temporary use. After the article has been used it is dropped into the cabinet 2.

When the article removing member 26 approaches the end of its right hand stroke the hook 36 will ride up on the member 51 and be in the path of the hook 52 so that the article removing member cannot be moved to pick up an article.

other article until another coin or check of the proper denomination has been inserted into the machine.

If the cable 17 is not employed then the article 5 will drop into a position accessible to the intending purchaser and can be removed through the delivery opening 12.

As the member 30 is moved towards the right it 10 will be apparent that the cam 34 rocks it, and the upper portion of the terminal 16' in proximity to the end of the slot 16 is rounded to facilitate the rocking of the article carrier 30.

It will now be apparent that we have devised 15 a new and useful vending machine which embodies the features of advantage enumerated as desirable in the statement of the invention and the above description, and while we have, in the present instance, shown and described a preferred embodiment thereof which will give in 20 practice satisfactory and reliable results, it is to be understood that this embodiment is susceptible of modification in various particulars without departing from the spirit or scope of the invention or sacrificing any of its advantages.

25 Having thus described our invention what we claim as new and desire to secure by Letters Patent, is:—

1. A vending machine adapted to vend articles provided with grommets, comprising a casing 30 having an article receiving compartment and a vending opening, an article retainer comprising

a bar having a detent and having its forward end downwardly deflected, a reciprocatory article removing member having a hook at one end to engage the grommet of an article on said retainer, and a detent at its opposite end, a spring to move said detent towards said retainer, means to actuate said member to effect the release of an article from its hook, and a spring carried by said retainer and over which said grommet passes and facilitating the removal of the grommet 85 from said hook.

2. A vending machine adapted to vend articles provided with grommets, comprising a casing having an article receiving compartment and a vending opening, a channelled bar having its upper face smooth and on which the grommets can slide, an article removing member movable in said channel having a hook to enter a grommet and carry it, and having its opposite end pointed, a spring to move said pointed end towards said 95 retainer, said retainer having a stop shoulder in the path of said pointed end, means to move said member to permit it to pass said stop shoulder, and a spring having one end secured to said retainer and its opposite end bent outwardly, 100 whereby when a grommet passes over it, the removal of the grommet from said hook is facilitated.
